DESIGN FOR A DRESS

Alice Engel, New York, N. Y.

Application March 25, 1939, Serial No. 83,834

Term of patent 3½ years

To all whom it may concern:

Be it known that I, Alice Engel, a citizen of the United States, residing in New York city, in the county of New York and State of New York, have invented a new, original, and ornamental Design for a Dress, of which the following is a specification, reference being had to the accompanying drawing, forming part thereof.

Fig. 1 is a front view of a dress showing my design, and

Fig. 2 is the rear view thereof.

The characteristic feature of my design resides in the combination of the specific net dress disclosed of the embroidered blouse section in association with the Shirred waistline and the matching embroidery on the skirt pockets, as shown.

I claim:

The ornamental design for a dress, substantially as shown and described.

ALICE ENGEL.
